ENGINE COOLING SYSTEM AND
STRUCTURE

Carl L. Blanton, Chester, Pa.

Application February 25, 1936, Serial No. 65,604

6 Claims. (Cl. 123—174)

This invention relates generally to an internal combustion engine type of locomotive and more particularly to an improved engine cooling system and structure therefor.

5 It is an object of my invention to provide an improved engine cooling system and self-contained structure with its component parts so functionally and structurally related as to form a relatively simple, compact and rugged apparatus that is comparatively economical in manufacture, maintenance and operation and provides efficient flow passages for the cooling water through the entire system.

In one specific aspect of the invention I accomplish the foregoing object by providing an improved engine bed having a water compartment or passages therein and arranged to support a radiator having direct communication with the water passages in the bed.

20 Other objects and advantages will be more apparent to those skilled in the art from the following description of the accompanying drawings in which:

Fig. 1 is a side elevation of an internal combustion engine type of locomotive embodying my invention;

Fig. 2 is an enlarged side elevation of the forward portion of the locomotive with parts broken away to show details of construction and with certain radiator sections omitted for purposes of clarity;

Fig. 3 is a perspective of the front end of the engine bed, showing the lower radiator tank embodied as a part of the engine bed together with an upper radiator tank suitably supported thereby;

Fig. 4 is a horizontal section taken substantially on the line 4—4 of Fig. 2 to show the manner of providing passage walls for the cooling air passing over the radiator;

Fig. 5 is a plan view of a modified form of upper radiator tank adapted to be used in my improved combination, parts of which are broken away to show details of construction;

45 Fig. 6 is a side elevation of Fig. 5 viewed in the direction of arrow A of Fig. 5 and parts of which are broken away to show details of construction.

In the particular embodiments of the invention, which are disclosed herein merely for the purpose of illustrating certain specific forms among possible others that the invention might take in practice, I have shown in Fig. 1 a conventional type of locomotive having a underframe 7 supported upon usual trucks 8 which may be provided with electric motors supplied with current

from an electric generator 9. The generator is driven by a suitable internal combustion engine 10 whose cooling liquid is circulated through a suitable air cooled radiator generally indicated at 11. The cab structure and control equipment do not, of course, form a part of my present invention and hence need not be described, except in so far as the front end of a hood is brought into supporting relation to the engine bed.

The engine bed as shown in Fig. 3 is herein considered to broadly comprise, as a self-contained unit, a cylinder base 12 and an integrally formed forwardly projecting radiator base generally indicated at 13, the cylinder base 12 being of any suitable shape or structure adapted for the particular design of engine used. The integral bed structure may be either cast or built up by welded plates.

The radiator base 13 comprises (Fig. 2) upper and lower horizontal walls 14 and 15 which are substantially the width of the cylinder base 12 adjacent thereto, while the forward portion spreads out laterally as indicated at 16 and 17 (Fig. 3). To insure maximum rigidity between the elements 12 and 13, there is provided gussets 18 and 19 preferably merged with side walls 20 (Fig. 2) for the horizontal walls 14 and 15.

Formed around the two sides and front end of the forward laterally projecting portion of base 13 are side channels 21, 22 and 23, these having preferably portions 24 (Fig. 3) raised above the upper horizontal wall 14. The side channels 21 and 22 thereby provide a substantial liquid pocket to which the lower end 25 of a series of radiator sections 26 is connected for communication therewith as well as having the necessary communication with the large water space formed in channels 21, 22 and 23. The inner wall of channels 21 and 22 may curve around as at 24' to terminate adjacent the forward end of the cylinder base. While the remaining inner space between the upper and lower walls 14 and 15 is preferably not used, yet it could be used for additional water space if desired while at the same time performing its present function of reinforcing said base.

A down draft air opening 29 for cooling the electric motors of trucks 8 extends through base 13 in the form of a suitably walled passage, two walls of which form the inner walls of channels 22 and 23. The blower for circulating this air is indicated at 30 (Fig. 2) and is driven by a suitable motor 31. This motor is supported upon a suitable base 31' formed preferably on the top horizontal wall 14.

An upper radiator tank is generally indicated at 32 (Fig. 3) supported upon a framework having upright channels 33 located at each corner of the forward laterally spread portion of base 13. The front and rear sets of vertical channels are connected by transverse channels or beams 33' preferably mitered with the vertical channels 33. The transverse channels thus provide an ample supporting surface upon which the tank 32 rests. The upper tank 32 comprises hollow sides 34 and 35 of rectangular box section connected to and communicating with end sections 36 and 37 which have a portion projecting above the elevations of sides 34 and 35. The end sections 36 and 37 are also of rectangular box section. The walls of these various sections may be suitably internally braced.

A series of upper radiator sections 39 are connected at 40 to the side channels 34 and 35 for communication therewith. The lower and upper ends respectively of the radiator sections 39 and 26 are connected to a box-shaped manifold 41 which in turn is secured to the front and back vertical channels 33. This improved arrangement 25 of radiator sections and intermediate manifold 41 insures not only a rigid framework for supporting the upper radiator tank 32 but also permits advantages to be obtained relative to the shorter radiator sections.

As shown in Fig. 2, a radiator fan 56 is mounted 30 on a vertical axis to be driven by a motor 46. This fan unit is supported upon and projects downwardly between two horizontal channel beams 43 (Fig. 3) secured to the transverse channels 33' of the framework which supports the upper radiator tank 32. To provide a circular passage for fan 45, a circular sheet metal wall 46', Fig. 2, is concentric to the fan blades while a horizontal sheet 47 fills in the space between said circular sheet 46' and the four corners of the upper radiator tank 32. As shown in Fig. 4, which is a section on line 4-4 of Fig. 2, a vertical sheet metal wall or panel 49 extends entirely transversely between the two forward vertical channels 33 and for the full length thereof. A similar vertical wall is provided between the rear set of vertical channels 33. Thus the fan 45 can only draw air laterally inwardly over the radiator sections on opposite sides of the supporting framework and thence discharge the air upwardly through a suitable opening 50 in the top of hood 51. Also blower 30 (Fig. 2) will draw air laterally inwardly over the radiator sections and discharge such air to the electric motors of trucks 8.

To provide a pleasing appearance for the front end of the hood, my improved radiator supporting structure is provided (Fig. 3) with a pair of forwardly projecting angle plates 53 and 54 suitably secured to the sides of channels 21 and 22 of the base 13. Also projecting forwardly from the front set of vertical channels 33 are a series of angle irons 54. A vertical framework consisting of channels or other suitable structural members is generally indicated at 55 supported by members 54. Sheet metal panels 56 extend upwardly over the side of said framework and across the front thereof.

In the event that it is desired to use certain of the radiator sections 26 and 39 (such as those specifically connected to legs 35 and 22) for cooling the engine lubricating oil, suitable partitions 57 and 58 (Fig. 3) are provided in the water leg 35 of the upper water tank while similar partitions generally indicated at 59 are provided in the channel 22, it being understood that in this particu-

lar arrangement the legs 21 and 34 are used entirely for water and hence remain in communication with the transverse legs and with that portion of legs 22 and 35 not used for oil. To avoid any possibility of leakage from the oil chambers 60 and 61 into the water chambers formed in the remaining portion of the upper and lower tanks, I have provided an additional set of partitions 62 and 63. The space between partitions 57 and 62 and between 59 and 63 is void and preferably provided with a suitable drain opening similar to the one at 76, Fig. 5.

In the modification shown in Figs. 5 and 6, the upper tank is an integral casting generally indicated at 65 supported upon vertical channels 66 corresponding to the channels 33 of Fig. 3. The channels 66 are secured directly to the sides of the casting as generally indicated at 67 while suitable transverse angle irons 68 connect the vertical channels and provide additional support for the under side of the tank 65. The radiator sections are secured respectively to the two sides 69 and 70 which are provided with openings 71 (Fig. 6) for communication with the chambers 72 and 73, the chambers 72 and 73 forming respectively the water and oil compartments. The oil compartment 73 is separated from the water compartment by a pair of double walled partitions 74 and 75, thereby forming a space which is void and provided with drain openings 76 to prevent leakage of oil into the water or vice versa. The fan opening 71' is circular and is substantially concentric to the outer wall of the tank 65. Liquid is received in inlet openings 77 and thence flows outwardly through the side openings 71 and down through the radiator sections into the intermediate manifold 41 and through the lower set of radiator sections into the base chambers from which water is drawn (Fig. 1) through a pipe 19 to a water pump 80 and thence through the cylinder jacket to a pipe 81 and the inlet 77. Oil is drawn upwardly from the engine crankcase sump through a pipe 82, pump 83 and thence through pipe 84 and inlet 78 to flow down through the upper and lower radiator sections to be forced under pressure through a pipe 85 to the engine parts to be lubricated.

The foregoing system of piping and pumps is used with both modifications shown in Figs. 3 and 5.

From the foregoing disclosure it is seen that I have provided a cooling system apparatus that is highly rigid, compact and self-contained with the engine bed, thereby avoiding the complications and cost of manufacture, installation and maintenance that are incident to the many prior art systems wherein a great many pipes and piping connections have been necessary. It is also seen that my improved arrangement is most conducive to efficient circulation of cooling air across the radiator sections with minimum structure for supporting the air circulating means, it also being noted that every advantage is taken to utilize various elements for a multiplicity of functions such for example as the blower 30 located within the radiator construction so as to induce flow of air over the radiator sections before such air is passed over the truck motors. This air may be slightly heated in passing over the sections, but it will still be adapted to effectively cool the truck motors.

It will of course be understood that various changes in details of construction and arrangement of parts may be made by those skilled in

the art without departing from the spirit of the invention as set forth in the appended claims.

I claim:

- 5 1. In combination, an engine bed having as a self-contained integral unit a cylinder base and a radiator base with a water chamber therein, an upper tank having horizontally spaced chambers with a vertically extending cooling air passageway therebetween, a frame projecting upwardly from the radiator base for supporting said upper tank, radiator sections supported by said radiator base and communicating with said chamber and tank, water chambers, and radiator sections communicating therewith.
- 10 2. In combination, an engine bed having as a self-contained integral unit a cylinder base and a radiator base provided with a water chamber, an upper tank having horizontally spaced chambers with a vertically extending cooling air passage-
way therebetween, means for supporting said upper tank by said radiator base, radiator sections extending from said chamber base to said upper tank at the sides thereof, and means for circu-
lating air horizontally and inwardly of said radi-
ator sections and thence upwardly through said vertical passageway.
- 15 3. In combination, an engine bed having as a self-contained integral unit a cylinder base and a radiator base provided with a water chamber, means forming an upper radiator chamber having a walled vertical opening extending there-
through, means for supporting said upper chamber by said radiator base, radiator sections sup-
ported at the sides of said upper chamber and
said radiator base, and a blower located within
said opening for circulating air horizontally and
inwardly over said radiator sections and thence
upwardly through said opening.

4. In combination, an engine bed having as a self-contained integral unit a cylinder base and a forwardly projecting radiator base, means forming a water channel around the sides and the end of said radiator base, means forming an upper tank of rectangular shape with chambers formed around the sides thereof and a vertical opening located between said sides, radiator sections connected to said channel in the base and to the upper tank, and means for circulating air horizontally and inwardly over said radiator sections and thence upwardly through said vertical opening.

5. In combination, an engine bed having as a self-contained integral unit a cylinder base and a radiator base, said radiator base having upper and lower horizontal walls, a water chamber formed between said walls, vertically extending radiator sections connected to said radiator base for communication with the chamber therein, an air passage extending downwardly through said upper and lower horizontal walls of said base, and a motor driven blower supported by said base for circulating air through said passage.

6. In combination, an engine bed having as a self-contained integral unit a cylinder base and a radiator base with a water chamber therein, an upper tank having horizontally spaced chambers with a vertically extending cooling air passageway therebetween, a frame projecting upwardly from the radiator base for supporting said upper tank, an intermediate manifold carried by said frame, and radiator sections comprising upper and lower portions connected to said manifold and respectively connected to and supported by the radiator base and to the upper tank for communication with the chambers therein.

CARL L. BLANTON.

CERTIFICATE OF CORRECTION.

Patent No. 2,124,523.

July 26, 1938.

CARL L. BLANTON.

It is hereby certified that error appears in the printed specification of the above numbered patent requiring correction as follows: Page 2, first column, line 30, for the reference numeral "56" read 45; page 3, first column, line 13, after the first comma and before "water" insert the words said umn, line 13, after the first comma and before "water" insert the words said radiator base and upper tank having partitions forming oil and; and that the said Letters Patent should be read with this correction therein that the same may conform to the record of the case in the Patent Office.

Signed and sealed this 30th day of August, A. D. 1938.

Henry Van Arsdale

Acting Commissioner of Patents.
